UNITED STATES PATENT OFFICE.

WILFRED J. TURENNE, OF DANVERS, MASSACHUSETTS.

ELECTRIC CUT-OUT AND FUSE.

Application filed October 6, 1922. Serial No. 592,757.

This invention relates to improvements in an electric cut-out and fuse construction and the principal object of the invention is to provide a device in which the fuse is so mounted as to insure complete severance of the fuse when it is heated above a predetermined fusing temperature.

A further object of the invention is to provide suitable means to receive and collect the molten material which results from the blowing of the fuse.

A further object of the invention is to provide a novel means for securing the cut-out device to a suitable support.

More specifically the invention relates to improvements in a cut-out and fuse construction for electrically heated flat irons and the object thereof is to provide a novel construction which can be readily mounted upon the flat iron and in which the fusible material, although protected from direct action of the heat of the heating unit and the base of the iron, will be so arranged as to be melted by the heat of the iron when the same exceeds a predetermined temperature and severance insured.

These and other objects and features of the invention will more fully appear from the following description and the accompanying drawings and will be particularly pointed out in the claims.

A preferred embodiment of the invention is illustrated in the accompanying drawings, in which,

Fig. 1 is a longitudinal vertical sectional view through an electrically heated flat iron and the novel cut-out and fuse plug embodying the invention, the casing containing the heating unit being shown in elevation;

Fig. 2 is a side elevation of a preferred form of fuse plug and fuse;

Fig. 3 is a sectional view on line 3-3 Fig. 1 viewed from above;

Fig. 4 is a sectional view on line 4-4 Fig. 1;

Fig. 5 is a detail view of a modified form of plug and fuse; and,

Fig. 6 is an elevation of the plug illustrated in Fig. 5 viewed from the side.

The present invention is illustrated herein as embodied in an electrically heated flat iron, but it will be understood that the novel cut-out and fuse may be employed in other relations to which it is applicable within the scope of the claims.

The flat iron illustrated in the drawing

comprises the usual metallic base 1 upon which a suitable heating unit is mounted. The heating unit is connected by suitable binding screws 2 and 3 to conductors 4 and 5 through which a suitable electric current is transmitted to the heating unit. The heating unit is enclosed in a suitable casing 6 as is usual in such constructions.

The flat iron is provided with a cover 65 plate 7 which rests at its lower edge upon a shoulder extending around the upper portion of the base of the flat iron and presents a substantially flat top 8. A suitable plug of insulating material 9 is mounted in 70 the cover and is provided with apertures to receive posts 10 and 11 to which a connector for the conductors of a suitable electric circuit may be detachably connected as is usual in devices of this character.

As illustrated herein the binding screw 2 is connected directly with the post 10 by the conductor 4 while the conductor 5, which leads from the binding screw 3, is connected to one of the terminals of the cut-out and 80 fuse plug mechanism to which the present invention relates.

The cut-out and fuse construction comprises a chambered casing 12, preferably of cylindrical form, having a preferably downwardly extending conoidal closed end or bottom 13 and a laterally extending flange 14 at its top which is adapted to rest upon the top of the cover 8 of the flat iron, or any other suitable support for the cut-out device. 90

One of the features of the present invention consists in providing novel means for supporting the casing of the cut-out device and retaining the same permanently in proper position. In the preferred embodiment of the invention illustrated herein a strap 15 of copper, or other suitable conducting material, surrounds and embraces the upper portion of the cylindrical, chambered member 12 and desirably is located directly beneath and preferably engages the under surface of an extension of the insulating member 9 of the flat iron.

The strap 15 is provided with an extension 16 which is twisted to present a flat 105 enlarged end 17 having an aperture to receive the lower end of the post 11. A nut 18 upon the screw threaded end of the post serves to clamp the end 17 of the extension of the strap against the under face of the 110 insulating member 9 of the flat iron and also to establish a good electric contact with

the end of the strap 15. The other end of the strap 15 is provided with an extension 19 which is folded back upon itself and extends within the casing and is bent downwardly to provide a yielding terminal 20 adapted to engage the co-operating terminal upon the fuse. A screw 21, which extends through the folded portion of the extension 19 and is screw threaded into the extension 13 of the strap 15, serves to clamp the strap firmly about the chambered insulating member or casing of the cut-out and fuse.

By reason of this construction the insulated cut-out casing is firmly retained in place and is electrically connected to the post 11 which is adapted to be connected into the electric circuit.

The other terminal for the cut-out and fuse plug is preferably somewhat similarly constructed. It comprises a strap 22 which extends around and embraces the insulating chambered member 12 and is provided with an extension 23 having an aperture therethrough to receive a screw 24. The other end of the strap 22 is likewise provided with an extension 25 which is folded back upon itself and provided with a downwardly extending spring terminal 26 adapted to engage a co-operating terminal upon the cut-out and fuse plug which will hereinafter be more fully described. The screw 24 which extends through the extension 23 is screw threaded into the folded extension 25 and when set up serves to clamp the strap firmly upon the chambered insulating member as illustrated in Fig. 4.

Various forms of cut-out and fuse plugs may be employed within the spirit and scope of the claims. Two preferred constructions are illustrated herein, one of which is shown in detail in Figs. 1 and 2, and the other of which is shown in detail in Figs. 5 and 6. In the construction illustrated in Figs. 1 and 2 the plug consists of a head 27 which preferably is provided with a knob or handle 28 and with a cylindrical post 29 which fits in the upper open end of the chamber of the insulating member 12. The plug is provided with an integral downward extension or fuse support 30 which has convex edges which fit snugly against the inner wall of the chamber of the insulating member and is provided with flat sides 31 and 32 upon which the legs of the fuse are secured. Thus the plug when in operative position divides the chamber of the insulating member into two compartments.

The lower end of the fuse-supporting member 30 desirably is made thinner and is provided with an aperture 33 therethrough.

The fuse may be of any suitable character adapted to be melted when subjected to a temperature in excess of a predetermined amount. In the construction illustrated in Figs. 1 and 2 the fuse is inserted through the

aperture 33 in the plug and bent into U-shape, the legs 34 and 35 extending alongside and preferably lying against the flat walls of the fuse-supporting extension 30 of the plug. The legs 34 and 35 are provided at their upper ends respectively with binding screws 36 and 37 which are seated in the fuse-supporting extension of the plug, these screws being so located as to contact respectively with the terminals 26 and 22 leading respectively to the binding screw 3 of the heating unit and the post 11 which forms one of the elements of the usual connector devices for a flat iron.

The aperture 33 through which the bent portion of the U-shaped fuse passes is located at a considerable distance above the closed bottom of the chambered insulating member 12 and acts to support the central portion of the fuse as it sags down under an excessive heat so that the fuse is enabled to extend a greater distance during the melting stage than would be the case if no support were provided for the central portion of the fuse.

By reason of this central support the severance of the fuse and the complete shutting off of the current when a predetermined temperature is exceeded is insured. The closed bottom of the receptacle serves to collect the fused material from which it can be removed readily after the fuse has blown.

Any other suitable means may be provided for supporting the downwardly extending U-shaped portion of the fuse in such a manner as to provide a sufficient space to insure severance of the fuse and thereby to avoid the failure of a sagging but unbroken fuse to cut off the supply of current to the heating unit promptly and effectively.

In Figs. 5 and 6 a different form of cut-out and fuse plug embodying the invention is illustrated in which the chamber to receive the sagging and melting fuse is located in the plug itself. In this construction the fuse plug comprises a head 38 having a knob or handle 39 and an enlarged portion or boss 40 adapted to fit a suitable socket 41 which desirably comprises a wall of insulating material. The plug is provided with a fuse-supporting extension 42 having parallel recesses 43 which receives the legs of a U-shaped fuse 44. The transverse loop or bend of the U-shaped fuse fits in a cross groove 45 which connects the recesses 43, these recesses being at a considerable distance from the end of the plug extension 41, thus providing a relatively long chamber below the loop or bend of the fuse.

The inner wall of the lower end of the plug extension desirably is screw threaded and the chamber is closed by a hollow plug 46 having screw threads upon its outer wall 47. The edges of the wall 47 desirably engage the ends of the legs of the fuse so that

the central hollow portion 48 of the plug provides a chamber which lies beneath the transverse or looped portion of the fuse. In this construction the edges 47 of the plug prevent the downward sagging of the legs of the loop when the fuse is subjected to an excessive temperature, while the chamber 48 is of sufficient depth and capacity to insure the breakage of the melting and sagging transverse looped portion of the fuse when the fuse is subjected to an excessive temperature.

Other means may, of course, be employed for supporting the transverse looped portion of the fuse within the spirit of the claims herein.

The upper ends of the legs of the fuse 44 are connected respectively to suitable metallic terminals 49 and 50 adapted to co-operate respectively with the circuit terminals 26 and 22. In this construction the fuse may be of the usual type, such as, a cylindrical or flat fuse inserted in the apertures 43 which extend longitudinally of the plug 25 until the ends of the fuse engage the terminals 49 and 50. Preferably, however, a suitable fusible metal is cast directly into these longitudinally extending apertures to form the U-shaped fuse illustrated.

30 The cut-out and fuse construction disclosed in all of the figures of the accompanying drawing is particularly applicable to devices in which the blowing of the fuse is caused by an external temperature as the insulation surrounding the fuse may be made of relatively thin material.

35 The invention is illustrated herein as applied to a flat iron and in this construction the lower end of the insulating member is shown as extending into a recess in the upper face of the base of the flat iron so that the lower or looped portion of the fuse is not only in proximity to the surface of the base of the iron, but also in proximity to 40 the heating unit and, consequently, in a most favorable position to be affected by an excessive temperature of the iron.

45 It will be understood that various changes in form, construction and arrangement of parts may be made within the spirit and scope of the claims and that the invention consists broadly in providing means for supporting the sagging portion of the fuse so that it will elongate to a breaking point 50 while melting, thus insuring the interruption of the current.

55 It will also be understood that while the fuse construction is primarily adapted for use in constructions in which the fuse is melted by an external temperature in excess of a predetermined amount, it will also be blown if an excessive current is supplied to the circuit.

60 The present embodiment of the invention is, therefore, illustrative and not restrictive

and various changes in form, construction and arrangement of parts may be made within the spirit and scope of the following claims.

Having thus described my invention, what 70 I claim as new, and desire to secure by Letters Patent, is:

1. An electric cut-out and fuse comprising a chambered member having a wall of insulating material closed at its lower end to 75 provide a receptacle of sufficient capacity to collect the molten material of a blown fuse and a fuse plug removably mounted therein having a support for the central portion of the fuse located at a sufficient distance from 80 the bottom of said receptacle to insure the breakage of the melting fuse by sagging before the molten material is collected in said receptacle and contact terminals for connecting the fuse in an electric circuit. 85

2. An electric cut-out and fuse comprising a chambered socket member having a wall of insulating material closed at its lower end to provide a receptacle of sufficient capacity to collect the molten material of a blown 90 fuse, a plug removably mounted in said socket member having a fuse support extending into said chamber dividing the same into two compartments communicating at their lower ends with said receptacle, a fuse carried by said supporting member leading from one compartment to the other through an aperture in said plug located at a sufficient distance above the end of said support to insure the breakage of the melting fuse by sagging before the molten material of the blown fuse is deposited in the receptacle and complementary contact members upon 95 said fuse and socket member. 100

3. An electric cut-out and fuse comprising a cylindrical chambered socket member of insulating material having a closed bottom to provide a receptacle of sufficient capacity to collect the molten material of a blown fuse, a plug of insulating material removably mounted in said socket member having a substantially rectangular fuse support extending into the chamber in said socket member and dividing said chamber into two compartments communicating at the lower ends with said receptacle, a U-shaped fuse having its legs mounted upon the flat faces of said extension and extending lengthwise thereof, means supporting the bend of the fuse located at a sufficient distance from the end of the support to insure breakage of the melting fuse and separation of the parts thereof by sagging before the molten material of the blown fuse is collected in the receptacle and complementary contact terminals upon said fuse and socket member. 110 115 120 125

4. A fuse plug comprising a depending fuse support of insulating material presenting parallel sides and having an aperture therethrough to receive the central portion 130

of a U-shaped fuse and located at a sufficient distance from the free end of the plug to insure breakage of the melting fuse before the sagging portion thereof extends beyond the lower end of the fuse and contact members for the free ends of the fuse adapted to be engaged by complementary contact members of the socket.

5. An electric cut-out and fuse comprising a chambered socket member of insulating material, a plug having a fuse support extending into said chamber, a fuse mounted upon said support provided with contact members, a combined contact terminal and support for said socket member comprising a band surrounding said socket member having a folded end portion extending through an aperture in said socket member to engage one of the terminals of the fuse and the opposite end portion of said band extended to provide a terminal, clamping means connecting the folded end portion to the extended portion, means connecting the terminal end portion of said band to a supporting member and a contact member engaging the other terminal of the fuse.
- 10 6. An electric cut-out and fuse comprising

a chambered socket member of insulating material, a plug having a fuse support extending into said chamber, a fuse mounted upon said support provided with contact members, a combined contact terminal and support for said socket member comprising a band surrounding said socket member having a folded end portion extending through an aperture in said socket member to engage one of the terminals of the fuse and the opposite end portion of said band extended to provide a terminal, clamping means connecting the folded end portion to the extended portion, means connecting the terminal end portion of said band to a supporting member and a contact member for the other terminal of the fuse comprising a band surrounding the socket member having a folded end portion extending through a recess in the socket member to engage the other terminal of the fuse and clamping means connecting the folded end portion to the other end portion of said band.

In testimony whereof, I have signed my name to this specification.

WILFRED J. TURENNE.
